MULTIPLE CONTROL APPARATUS

Lester E. Spray, Wilkinsburg, Pa., assignor to The Union Switch & Signal Company, Swissvale, Pa., a corporation of Pennsylvania

Application December 3, 1928, Serial No. 323,286
Renewed February 10, 1936

82 Claims. (Cl. 246—134)

My invention relates to multiple control apparatus and is particularly adapted for, though not limited to, the control of the railway track switches and signals in a railway switching or interlocking layout.

One feature of my invention is the provision of means for controlling each of various partly inter-inclusive groups of devices by only one or by only two manually operable means. Another feature of my invention is the provision of interlocking control without the use of mechanically interlocked levers.

More particularly, the principal object of my invention is the provision of a system of route interlocking in which the switches and signals of a railway track layout are controlled by means of route buttons or miniature levers which are free to be moved to any of their positions at any time, and in which the interlocking necessary for proper operation is effected by means of suitably interlocked circuits for controlling the switches and signals, in lieu of interlocking between levers as generally employed heretofore.

A feature of one form of my invention is the provision of a separate route button of the rotary type for each route operable in one direction or another according to the direction of traffic to be established over the route.

The object of a second form of my invention is to facilitate the control of railway traffic by the provision of a control board comprising a miniature diagram of the track layout with the route buttons mounted thereon at points corresponding to the ends of the routes. In this form, the track switches are operated as required for a route and the corresponding signal is then cleared automatically, in response to a single operation of the pair of buttons identifying the opposite ends of the desired route, but only if traffic conditions are proper. The route set-up may then be cancelled, to permit the establishment of a different route, by restoring the operated buttons to normal. However, if this is done while the route is occupied by a train, the switch or switches in each track section of the route will be held locked in their last operated positions irrespective of the positions of the route buttons, until the train successively occupies and vacates that track section of the route.

The apparatus is also arranged to permit the signals for the main routes more frequently used to clear immediately in response to the operation of the route levers, the track switches being normally held in the positions required for these

routes by the restoration to normal of the route buttons for other routes.

Another feature of my invention resides in the arrangement of the indication apparatus of the operator's control board, which includes not only the usual lamps for indicating the condition of the track sections and the positions of the track switches of the layout, but also includes lamps for indicating when the track switches are free to be operated by the buttons and for indicating when the last track switch to respond assumes the required position.

Another feature of my invention relates to the provision for the control of auxiliary call-on signals in a system of this character.

I will describe two forms of apparatus embodying my invention, and will then point out the novel features thereof in claims.

In the accompanying drawings, Figs. 1 to 10 inclusive are diagrammatic views showing the constituent parts of one form of apparatus embodying my invention, and Figs. 11 to 15 inclusive are diagrammatic views showing changes in and additions to the apparatus of Figs. 1 to 10 as included in another form of apparatus also embodying my invention.

Similar reference characters refer to similar parts in each of the views.

Referring first to Figs. 1 to 10 which illustrate one form of apparatus embodying my invention, Fig. 1 shows a stretch of double track railway, tracks *aa* and *bb* of which are interconnected through crossover *ee* with which they are respectively joined by switches *H2* and *H2a*, and are likewise interconnected by crossover *ff* with which they are respectively joined by switches *H3* and *H3a*. Tracks *aa* and *bb* are also respectively joined to passing sidings *cc* and *dd* by switches *H4* and *H1*.

The reference characters *1* and *1a* designate the rails of track *aa*, and the reference characters *2* and *2a* designate the rails of track *bb*. These rails are divided by insulated joints *3* to form a plurality of track sections *a—A, A—E, B—D*, and *D—d*. Each of these track sections is supplied with current by a battery *4* connected across the rails adjacent one end of the section. A track relay, designated by the reference character *T* with a suitable distinguishing suffix, is connected across the rails adjacent the opposite end of each track section. Portions of crossovers *ee* and *ff* and siding *cc* are connected in multiple with section *A—E*, by wires *448*, and will therefore be referred to hereinafter collectively with section *A—E* as section *A—F—E*. Similar

40

30

35

45

50

55

ly, portions of crossovers *ee* and *ff* and siding *dd* are connected in multiple with section *B—D*, by wires 449, and will likewise be referred to hereinafter collectively with section *B—D* as section 5 *B—C—D*.

The reference character *S*, with a distinguishing suffix, designates a signal which is placed adjacent each of the points *A*, *B*, *C*, *D*, *E*, and *F*, respectively, and which as here shown is of the 10 semaphore type. Signals *S1a*, *S1b*, and *S2* are mounted on a common mast 446, and signals *S5a*, *S5b*, and *S5c* are mounted on a common mast 447. Signals *S1a*, *S1b*, *S2*, *S3*, and *S4* govern 15 eastbound traffic moves, that is, moves which are made over the stretch of track from left to right as illustrated in the drawings, and signals *S5a*, *S5b*, *S5c*, *S6*, and *S7* govern westbound traffic moves, that is, moves which are made over 20 the stretch of track from right to left as illustrated in the drawings.

Between the group of eastbound signals and the group of westbound signals, 11 different routes may be established according to the positions of the various switches. Over each of these 25 routes, traffic can proceed in either direction, that is, from west to east or from east to west. The arrangements of the switches for these various routes are as given in the following table:

- 30 *Route 1.*—*A* to *E*, switches *H2*, *H3*, and *H4* normal.
- Route 2.*—*A* to *F*, switches *H2* and *H3* normal, and *H4* reversed.
- Route 3.*—*A* to *D*, switches *H2* and *H2a* reversed, and *H3a* normal.
- 35 *Route 4.*—*A* to *E*, switches *H2*, *H2a*, *H3a* and *H3* reversed, and *H4* normal.
- Route 5.*—*A* to *F*, switches *H2*, *H2a*, *H3a*, *H3*, and *H4* reversed.
- 40 *Route 6.*—*B* to *D*, switches *H1*, *H2a*, and *H3a* normal.
- Route 7.*—*B* to *E*, switches *H1*, *H2a*, and *H4* normal, and *H3a* and *H3* reversed.
- Route 8.*—*B* to *F*, switches *H1* and *H2a* normal, and *H3a*, *H3*, and *H4* reversed.
- 45 *Route 9.*—*C* to *D*, switch *H1* reversed, and switches *H2a* and *H3a* normal.
- Route 10.*—*C* to *E*, switches *H1*, *H3a*, and *H3* reversed, and *H2a* and *H4* normal.
- 50 *Route 11.*—*C* to *F*, switches *H1*, *H3a*, *H3* and *H4* reversed, and *H2a* normal.

Track sections *A—F—E* and *B—C—D*, in which the switches are located and which are between the two groups of signals, are known as detector sections. Track sections *a—A* and *D—d*, in the rear of signals *S1a* and *S5a*, respectively, are known as approach track sections.

A route locking relay, designated by the reference character *VE*, prevents the operation of switch *H4* while an eastbound train occupies section *B—C—D* with switches *H3* and *H3a* reversed. Similarly, a route locking relay, designated by the reference *VW*, prevents the operation of switch *H1* while a westbound train occupies section *A—F—E* with switches *H3* and *H3a* reversed.

Each switch *H* is operated by a motor, designated by the reference character *M* with a suffix corresponding with that of the reference character *H* for the respective switch. Each motor 70 *M* comprises an armature 346 and a field winding 347. The motors *M3* and *M3a*, for operating switches *H3* and *H3a* respectively of crossover *ff*, are controlled in multiple by pole-changing contacts of a polarized relay *m3*. The control of the motors for operating switches *H2* and

5 *H2a*, of crossover *ee*, is similar to that for motors *M3* and *M3a* and is therefore not shown in the drawings. Motor *M4*, for operating switch *H4*, is controlled by pole-changing contacts of a polarized relay *m4*. The control for the motor of switch *H1* is similar to that for motor *M4*, and is therefore omitted from the drawings.

Operated in conjunction with each switch is a circuit controller, designated by the reference character *y* with a suffix corresponding with that of the reference character *H* of the respective switch. Contacts 348, operated by these circuit controllers and included in the control circuits of switch motors *M*, are closed at all times except while the respective switches are in their normal position. Contacts 349, operated by these circuit controllers and which are also included in the control circuits of switch motors *M*, are closed at all times except while the respective switches are in their reverse position.

The circuit controller *y4*, for switch *H4*, is provided with pole-changing contacts 13 and 14 for controlling the polarized switch indication relay *h4* that the contacts of this relay will be closed in their normal direction while switch *H4* is normal, and will be closed in their reverse direction while switch *H4* is reversed. The control of relay *h1*, by the circuit controller for switch *H1*, is similar to that for relay *h4*, and is therefore not shown in the drawings. Switch circuit controller *y3* is provided with contacts 21 and 22, and circuit controller *y3a* is provided with contacts 15, 16, 17, and 18, which are so associated in the control of the polarized switch indication relay *h3* as to cause the contacts of relay *h3* to be closed in their normal direction while switches *H3* and *H3a* are in their normal position and to be closed in their reverse direction while switches *H3* and *H3a* are reversed. The control of polarized switch indication relay *h2*, by switches *H2* and *H2a*, is similar to that for relay *h3* by switches *H3* and *H3a*, and is therefore not shown in the drawings.

Each of the signals shown in the drawings operates a circuit controller having contacts closed only while the respective signal is indicating "stop". Reference character *N*, with a distinguishing suffix, designates a relay, known as a back locking relay, which is controlled by such contacts of several of these signals.

Approach locking relays *P1* and *P5* prevent the operation of the switches in each route beginning at point *A* or *D* while the respective approach track relay *T1* or *T4* is de-energized and a respective adjacent signal on mast 446 or 447 is indicating "proceed". Relays *P1* and *P5* are so controlled that, after becoming de-energized by a train entering the respective approach track section while a respective signal is indicating "proceed," they can, while the respective approach track relay is still de-energized, again become energized only through a back contact of the track relay for the adjacent detector track section or through a time releasing device contact which will become closed only upon the lapse of a measured interval of time after the beginning of the operation of the respective device. Stick locking relay *Q3* becomes de-energized when either signal *S3* or *S4* is operated to its "proceed" position, thereby de-energizing back locking relay *N3*. Relay *Q3* can then again become energized only upon the de-energization of detector track relay *T3* or by the operation of a time releasing device *J3*. Relay *Q6*, associated with signals *S6* and *S7*, is controlled similarly to relay *Q3*. Ap- 75

proach and stick locking relays P and Q, while de-energized, prevent the operation of each switch in the route governed by the signals associated in the control of these relays, thus enforcing, after a respective signal has been returned to its "stop" position, the lapse of a measured time interval before the switches in the route governed by the signal can again be operated.

In each of the drawings, the contacts operated by the various relays or by the time releases J are identified by numbers, such numbers having suitable distinguishing exponents when such contacts are not shown adjacent the respective relay or release by which they are operated. The exponent for each of these contact numbers comprises the reference character and suffix of the respective relay or release, for example, the exponent T², for contact 177^{T²} shown in one of the pick-up circuits of relay VE in Fig. 1, comprises the reference character T and its suffix 2 of track relay T² which operates contact 177^{T²}. Similarly, exponent J³ of contact 168^{J³} in a pick-up circuit for relay P⁵, comprises reference character J and suffix 3 of time release J³ which is shown with a pick-up circuit of relay Q³ and which operates contact 168^{J³}.

Fig. 2 shows a lever G, to which I will refer as a "route lever", and a lever g, to which I will refer as a "call-on lever." These route and call-on levers are provided with contacts but are without any form of mechanical locking.

Each route is controlled by a route lever G, lever G¹ controlling route 1, lever G² controlling route 2, etc., and hence there are 11 of these levers since there are 11 routes. Each lever G has 5 positions, comprising a normal position n, a first and a second reverse position designated f and r respectively, and a third and a fourth reverse position designated b and p respectively. Each lever G is provided with contacts closed while the lever is in its n position, with contacts closed while the lever is in its p position, with contacts closed while the lever is in its p or its b position or at any intermediate point, with contacts closed while the lever is in its p or its f position or at any intermediate point, with contacts closed while the lever is in its r position, with contacts closed while the lever is in its r or f position or at any intermediate point, and with contacts closed while the lever is in its r or its b position or at any intermediate point.

The operation of each of these levers G to its f, r, b, or p position causes each switch in the respective route to be operated to the position required by the route, other conditions being right as will be explained hereinafter. If a lever G is operated to its p position, the westbound signal governing over the respective route will clear as soon as all switches in the route are arranged in their proper positions. If the lever is operated to its r position, the eastbound signal for governing over the same route will clear as soon as all switches in the route are arranged in their proper positions. Each switch in one of its positions, normal or reverse, is included in each route of a respective group of several routes and hence the operation of each switch to its normal position or to its reverse position is controlled by any one of a respective group of route levers. Each signal is controlled by the route lever for each route over which the signal governs.

Call-on levers g have two positions, a normal position n and a reverse position r, and are provided with contacts closed in the r position only.

Call-on lever g² constitutes means for providing

a call-on indication of signal S² when either signal S^{1a} or S^{1b} will not clear on account of the de-energization of one of the track relays controlling these signals. Similarly, a call-on indication of signal S^{5c} is controlled by lever g⁵ when signal S^{5a} or S^{5b} cannot be cleared because of the de-energization of one of the track relays controlling these signals.

In Fig. 3, circuits are shown for normal and reverse switch control relays designated respectively by the reference characters X and R with distinguishing suffixes. Each reverse control relay R is controlled by a circuit including, in multiple with each other, contacts closed by the route levers for all routes which include the respective switch in its reverse position, each such contact being closed while the lever is in its first or second reverse position or while the lever is in its third or fourth reverse position. Each normal control relay X is controlled by a circuit including, in multiple with each other, a series path through contacts closed in the normal position by all levers for routes which include the respective switch in its reverse position and multiple paths through contacts closed by the route levers for all routes which include the respective switch in its normal position, each contact in such multiple paths being closed while the respective lever is in its first or second reverse position or while the lever is in its third or fourth reverse position.

Indicators, designated by the reference eH followed by a distinguishing numeral, and here shown as electric lamps, are associated with the control of each normal control relay X and the respective reverse control relay R. Current is supplied to each relay X, the respective relay R, and the respective indicator eH, in multiple, by a path through a front contact of the track relay for the detector section in which the respective switch is located, through a front contact of the respective route locking relay, through front contacts of all approach and stick locking relays P and Q for routes which include the respective switch, and by front contacts of the back locking relays N for all signals which govern over the switch.

Fig. 4 shows circuits for a polarized switch control relay m¹ which is controlled by relays R¹ and X¹. Relay m¹ is energized in its normal direction while relay X¹ is energized, and is energized in its reverse direction while relay R¹ is energized and relay X¹ is de-energized. When both relays R¹ and X¹ are de-energized, relay m¹ will continue energized, through a polarized stick circuit, in the last previous direction of energization. The circuits for relays m², m³, and m⁴ are similar to those for relay m¹, and are therefore not shown in the drawings.

Fig. 5 shows circuits for stick relays t² and t³. Relay t² provides stick control of signals S^{1a} and S^{1b}, and relay t³ provides stick control of signals S^{5a} and S^{5b}.

In Fig. 6, approach and detector track circuit indicators are shown, lamp eT² being controlled by track relay T², indicator et² being controlled by stick relay t², and indicator eT¹ being controlled by track relay T¹. The circuits for indicators eT³, et³, and eT⁴ are similar respectively to those for indicators eT², et², and eT¹, and are therefore not shown in the drawings.

In Fig. 7, circuits are shown for switch position indicators eR¹ and eX¹ which are controlled by reverse or normal contacts respectively, of switch indication relay h¹ for switch H¹. Indicators eR², eR³, and eR⁴ are controlled, similar-

ly to indicator $eR1$, by reverse contacts of the respective switch indication relays $h2$, $h3$ and $h4$, and indicators $eX2$, $eX3$, and $eX4$ are controlled, similarly to indicator $eX1$, by normal contacts of the respective switch indication relays.

In Fig. 8, a circuit is shown for a signal indicator $eN1$ which is controlled by a back contact of back locking relay $N1$. Indicators $eN3$, $eN5$, and $eN6$ are similarly controlled by the respective back locking relays $N3$, $N5$, and $N6$.

Fig. 9 shows a track diagram and a control chart which can be located adjacent levers G and g for the information of the leverman in arranging the various routes. Reference characters H and S , with distinguishing suffixes, are shown adjacent the switch and signal symbols respectively on the track diagram. Also, adjacent each signal symbol, the lever and the position of that lever for controlling the signal are indicated. For example, above the symbol for signal $S4$, the designation "G9—10—11r" indicates that signal $S4$ can be cleared by any one of levers $G9$, $G10$, or $G11$ while in its r position. Similarly, the designation $g2—G3—4—5r$, adjacent the symbol for signal $S2$, indicates that signal $S2$ can be cleared by route levers $G3$, $G4$, or $G5$, or by call-on lever $g2$ each in its r position.

Fig. 10 is a diagram of the controls of the signals shown in Fig. 1. Signal control indicators, each designated by the reference eS with a suffix corresponding with that of the reference character S of a respective signal, are associated with the controls of the signals.

Referring now to Figs. 11 to 15, changes in and additions to the apparatus of Figs. 1 to 10 inclusive are here shown for the second form of apparatus embodying my invention. The second form of apparatus includes parts exactly as shown in Figs. 1, 2, 4, 6, 7, and 8, but differs from the first form of apparatus in respect to Figs. 3, 5, 9, and 10 as shown in Figs. 11 to 15 inclusive. Whereas the first form of apparatus, as shown in Figs. 1 to 10 inclusive, provides a lever for each of the 11 routes as designated in the control chart of Fig. 9, whereby each route can be arranged and a respective signal cleared by a single lever manipulation, the second form of apparatus embodying my invention provides but one lever or route button for each location constituting the entrance or exit end of one or more routes, so that there are only 7 levers for controlling the 11 routes. This form of the apparatus requires the manipulation of the pair of levers associated with the opposite ends of a route for arranging each route and clearing the respective signal.

In the second form of apparatus, a push button and a stick relay are substituted for each call-on lever g of the first form. However, either the call-on lever g of the first form of apparatus or the push button and stick relay of the second form of apparatus as shown in Fig. 15 could be used with either the first or the second form of apparatus.

Fig. 11 shows an arrangement of a combined track diagram and operating board for use with the second form of apparatus, comprising a miniature representation of the track layout to be controlled, upon which the route levers are mounted at points corresponding to the ends of the routes which they control.

To arrange for a move by the route from A to F over switch $H2$ normal, the leverman operates levers $G1$ and $G7$ to their f positions if he wishes signal $S1b$ to remain at "stop" after the switches have been moved to the positions required by the route, and if he then later wishes to clear signal

$S1b$ which governs over this route, he will advance lever $G1$ to its r position. If, on the other hand, the leverman should desire the signal to clear as soon as the switches are arranged in their proper positions, he at once operates lever $G1$ to its r position and lever $G7$ to either its f or its r position.

For a move from A to E over switch $H2$ normal, the leverman similarly operates levers $G1$ and $G6$; for a move from A to D, the leverman similarly operates levers $G2$ and $G5$; and for a move from A to E over switches $H2$, $H2a$, $H3a$, and $H3$ reversed, he similarly operates levers $G2$ and $G6$. The leverman can likewise arrange for a move by any of the other routes, such as from points B or C to points D, E, or F, by operating levers $G3$ or $G4$ respectively with levers $G5$, $G6$, or $G7$ respectively.

To arrange for moves in the opposite direction, the leverman operates the respective levers to the b or the p position instead of to the f or r positions respectively. For example, to arrange the route and clear signal $S7$ for a move from F to A over switch $H3$ normal, the leverman operates lever $G7$ to the p position and lever $G1$ to either its b or its p position.

Fig. 12 shows modified circuits for stick relays $t2$ and $t3$ of Fig. 5.

Fig. 13 shows portions of the circuits of normal and reverse switch control relays X and R as modified from the scheme in Fig. 3. Current is supplied to relays X and R , and to indicators eH , through front contacts of the same relays and with such contacts in the same arrangements as in Fig. 3 as far as wires 351, 352, 353, and 354, and thence through lever contacts as shown in Fig. 13.

Fig. 14 shows the control circuits for the signals and the signal control indicators as modified for the second form of apparatus.

Fig. 15 shows circuits for the call-on relays K controlled by push buttons U , these being substituted for the call-on levers g of the first form of apparatus as already mentioned.

Having thus described, in general, the arrangement and location of the various parts comprising my invention, I will now proceed to explain the operation of the apparatus.

Referring to the drawings, all parts are shown in their normal condition, that is, the track sections are clear, the switches are in their normal positions, all signals are at "stop," all levers are in their normal positions, and certain indicator lamps are lighted.

As shown in Fig. 1, each of the back locking relays N is energized on account of the respective signal arms being in the "stop" position. The circuit for relay $N1$ passes from terminal x of a source of current not shown in the drawings, through contacts 23, 24, and 25 operated by signals $S2$, $S1b$, and $S1a$ respectively, and the winding of relay $N1$ to terminal o of the same source of current. Relay $N3$ is energized by a similar circuit passing from terminal x , through contacts 26 and 27 of signals $S4$ and $S3$ respectively, and the winding of relay $N3$ to terminal o . Relay $N5$ is energized by current flowing from terminal x , through contacts 28, 29, and 30 of signals $S5c$, $S5b$, and $S5a$, respectively, and the winding of relay $N5$ to terminal o . Relay $N6$ is energized by current flowing from terminal x , through contacts 31 and 32 of signals $S6$ and $S7$ respectively, and the winding of relay $N6$ to terminal o .

Approach locking relays $P1$ and $P5$ are also energized. A pick-up circuit for relay $P1$ is

- closed, passing from terminal x , through contact 159^{T1} , and the winding of relay $P1$ to terminal o . A stick circuit for relay $P1$ is also closed, passing from terminal x , through contact 160 of relay $N1$, contact 161 of relay $P1$, and the winding of relay $P1$ to terminal o . Current flows through the winding of relay $P5$ by a pick-up circuit passing from terminal x , through contact 164^{T4} , and the winding of relay $P5$ to terminal o . At the same time, current flows by a stick circuit from terminal x , through contact 165 of relay $N5$, contact 166 of relay $P5$, and the winding of relay $P5$ to terminal o .

Stick locking relays $Q3$ and $Q6$ are energized by their stick circuits only. The stick circuit of relay $Q3$ passes from terminal x , through contact 169 of relay $N3$, contact 170 of relay $Q3$, and the winding of relay $Q3$ to terminal o . The stick circuit of relay $Q6$ passes from terminal x , through contact 173 of relay $N6$, contact 174 of relay $Q6$, and the winding of relay $Q6$ to terminal o .

Route locking relays VE and VW are also energized, both pick-up and stick circuits for these relays being closed. A first pick-up circuit for relay VE is controlled by contacts 177^{T2} and 178^{T3} , and a second pick-up circuit for relay VE is controlled by a normal contact 179^{h3} . A stick circuit for relay VE passes from terminal x , through contact 180 of relay $P1$, contact 181 of relay $Q3$, contact 182 of relay VE , and the winding of relay VE to terminal o . A first pick-up circuit for relay VW is controlled by contact 183^{T2} , and a second pick-up circuit is controlled by contact 184^{h3} . The stick circuit for this relay is controlled by contact 185 of relay $Q6$.

With switch $H4$ in its normal position, contacts 13 and 14 of circuit controller $y4$ connect with terminals $13a$ and $14a$ respectively, causing current to be supplied to relay $h4$ in the normal direction, and the contacts of relay $h4$ are therefore closed in their normal position. With switches $H3$ and $H3a$ in their normal position, contacts 21 and 22 of circuit controller $y3$ connect with terminals $21a$ and $22a$ respectively, and contacts 15 and 17 of circuit controller $y3a$ connect with terminals $15a$ and $17a$ respectively, and hence current flows in the normal direction through the winding of relay $h3$ causing the contacts of relay $h3$ to be closed in their normal position. Similarly, relays $h1$ and $h2$ are energized in the normal direction, and their contacts are closed in the normal position.

Normal switch control relay $X1$, shown in Fig. 3, is energized by current passing from terminal x , through contacts 43^{T3} , 44^{Q3} , 45^{P5} , 46^{N3} , 47^{N5} , 48^{N6} , 49^{Q6} , 50^{VW} , wire 351 , contacts 58^{G9} , 59^{G10} , 60^{G11} , and winding of relay $X1$ to terminal o . A branch path is also closed, passing from contact 47^{N5} , through contact 51^{h3} to wire 351 . Normal switch control indicator lamp $eH1$ is lighted by current flowing in the circuit of relay $X1$ as far as wire 351 , and thence through lamp $eH1$ to terminal o . Normal switch control relay $X2$ is energized by current flowing in the circuit just traced for relay $X1$ as far as contact 47^{N5} , thence through contacts 67^{N6} , 68^{N1} , 69^{P1} , 70^{Q6} , 71^{T2} , wire 352 , contacts 78^{G3} , 79^{G4} , 80^{G5} , and the winding of relay $X2$ to terminal o . Normal switch control indicator lamp $eH2$ is lighted by current flowing in the circuit of relay $X2$ as far as wire 352 , and thence through lamp $eH2$ to terminal o . Relays $X3$ and $X4$ and lamps $eH3$ and $eH4$ are energized by circuits which, being similar to those just traced for relays $X1$ and $X2$ and lamps

$eH1$ and $eH2$ respectively, will be readily understood from the drawings.

Relay $m1$, shown in Fig. 4, is energized in its normal direction by its normal pick-up circuit passing from terminal x , through contact 36^{X1} , winding of relay $m1$, and contact 34^{X1} to terminal o . Relays $m2$, $m3$, and $m4$ are similarly energized by their respective normal pick-up circuits.

Relays $t2$ and $t3$, shown in Fig. 5, are energized, both the pick-up and stick circuits for each of these relays being closed. The pick-up circuit for relay $t2$ is controlled by contacts 5^{G1} and 6^{G2} which are closed while the respective levers are in either their p or their f position or at any intermediate point. The stick circuit for relay $t2$ is closed through contact 7^{T2} . The pick-up circuit for relay $t3$ is controlled by contacts 9^{G6} and 10^{G8} which are closed while the respective levers are in their b or their r position or at any intermediate point. The stick circuit for relay $t3$ is controlled by contact 11^{T3} .

Each of the indicator lamps shown in Fig. 6 is lighted, since the respective controlling relays T and t are energized.

Each indicator lamp eX shown in Fig. 7 is lighted, since the respective switch indication relay h is energized in its normal direction and the respective switch indication relay contact, such as 190^{h1} in the circuit of lamp $eX1$, is therefore closed in its normal position.

I will now assume that the leverman desires to arrange for a train to move over route l from A to E. He therefore operates lever $G1$ to its r position, completing around contacts 78^{G3} , 79^{G4} , and 80^{G5} in the circuit of relay $X2$, a branch path through contact 81^{G1} , and completing, for relays $X3$ and $X4$, branch paths through contacts 125^{G1} and 151^{G1} , respectively. It is clear that this operation of lever $G1$ does not change the position of any of the switches in route l , but it does by completing the control circuit for signal $S1a$, shown in Fig. 10, cause signal $S1a$ to be operated to its "proceed" position by current flowing from terminal x at the right of Fig. 10, through contacts 229^{N6} , 230^{G10} , 231^{G7} , 232^{G4} , 233^{G1} , 240^{G11} , 241^{G8} , 242^{G5} , 243^{G2} , 244^{h4} , 245^{J1} , 246^{h3} , 247^{h2} , 248^{G11} , 249^{G10} , 250^{G8} , 251^{G7} , 252^{G5} , 253^{G4} , 254^{G1} , 255^{h2} , 256^{h2} , and the operating mechanism of signal $S1a$ to terminal o . Signal control indicator lamp $eS1a$ becomes lighted by the circuit traced for the operating mechanism of signal $S1a$ through contact 256^{T2} , and thence through lamp $eS1a$ to terminal o .

When the arm of signal $S1a$ leaves its "stop" position, contact 25 of signal $S1a$ opens, thereby de-energizing relay $N1$ which in turn opens the stick circuit of approach locking relay $P1$. Relay $P1$, however, continues energized by its pick-up circuit through contact 159^{T1} . With lever $G1$ in its r position, contact 5^{G1} in the pick-up circuit of relay $t2$ is open but relay $t2$ continues energized by its stick circuit through contact 7^{T2} . Relay $N1$, upon becoming de-energized, closes its contact 191^{N1} thereby lighting indicator lamp $eN1$ shown in Fig. 8. Relay $N1$, upon becoming de-energized, de-energizes relay $X2$ by opening contact 68^{N1} , and de-energizes relays $X3$ and $X4$ by opening contact 100^{N1} .

The normal pick-up circuits for relays $m2$, $m3$, and $m4$, being controlled by front contacts of normal control relays $X2$, $X3$, and $X4$ similarly to the manner in which relay $m1$ is controlled by contacts 34^{X1} and 36^{X1} are now opened, but normal stick circuits are at once closed for these polarized relays through back contacts of the

respective normal control relays X^2 , X^3 , and X^4 and back contacts of the respective reverse control relays R^2 , R^3 , and R^4 , causing relays m^2 , m^3 , and m^4 to continue energized in the normal direction. The normal stick circuits for relays m^2 , m^3 and m^4 are similar to the normal stick circuit shown for relay m^1 passing from terminal X , through contacts 39^{R1} and 40^{X1} , contact $42a-42$ of relay m^1 , winding of relay m^1 , contact $41-41a$ of relay m^1 , and contacts 38^{X1} and 37^{R1} to terminal o .

An eastbound train, approaching signal $S1a$ after route 1 has been arranged as already described, de-energizes approach track relay T^1 , thereby opening contact 189^{T1} and causing the light of lamp eT^1 to be extinguished. At the same time relay T^1 opens its contact 159^{T1} in the pick-up circuit of approach locking relay P^1 which thus becomes de-energized since its stick circuit has already been opened at contact 160 of back locking relay N^1 . Relay P^1 , upon becoming de-energized, opens its contact 69^{P1} in the circuit for relay X^2 , and opens its contact 99^{P1} in the circuits for relays X^3 and X^4 .

As the train proceeds past signal $S1a$, entering section $A-F-E$, detector track relay T^2 becomes de-energized, opening its contact 71^{T2} in the circuit of relay X^2 , which, however, is already open at contacts 68^{N1} and 69^{P1} . Relay T^2 also opens its contact 97^{T2} in the circuits of relays X^3 and X^4 which are, however, already open at contacts 99^{P1} and 100^{N1} . Relay T^2 , by opening its contact 187^{T2} , extinguishes the light of indicator lamp eT^2 . Relay T^2 , upon becoming de-energized, also opens its contact 7^2 in the stick circuit for relay t^2 , which is thereby de-energized since its pick-up circuit has already been opened at contact 5^{G1} when lever G^1 was operated to its r position. Relay t^2 , upon becoming de-energized, opens its contact 256^{t2} in the circuit of the operating mechanism of signal $S1a$, causing the arm of signal $S1a$ to return to its "stop" position and the light of indicator lamp $eS1a$ to be extinguished. Relay t^2 also opens its contact 188^{t2} , extinguishing the light of indicator lamp eT^2 . The de-energization of relay T^2 causes approach locking relay P^1 to become energized by its pick-up circuit passing through contact 162^{T2} .

The arm of signal $S1a$, upon returning to its "stop" position, causes back locking relay N^1 to again become energized. Relay N^1 then opens its contact 191^{N1} , extinguishing the light of lamp eN^1 shown in Fig. 8, and, by its contact 160 , again closes the stick circuit of approach locking relay P^1 . Relays N^1 and P^1 now being energized, contacts 68^{N1} and 69^{P1} are again closed in the circuit of relay X^2 , and contacts 100^{N1} and 99^{P1} are again closed in the circuits of relays X^3 and X^4 . The circuit for relay X^2 , however, continues open at contact 71^{T2} , and the circuits for relays X^3 and X^4 continue open at contact 97^{T2} .

As soon as the train leaves section $a-A$, relay T^1 again becomes energized and closes its contact 189^{T1} , thereby causing indicator lamp eT^1 to again be lighted. Relay T^1 also closes its contact 159^{T1} , thereby closing the pick-up circuit previously traced through this contact for relay P^1 . Relay P^1 is, however, at this time already energized by its stick circuit and by its pick-up circuit through contact 162^{T2} .

When the train moves out of section $A-F-E$, relay T^2 again becomes energized, closing its contact 71^{T2} which completes the circuit of relay X^2 , and closes its contact 97^{T2} which completes

the circuits of relays X^3 and X^4 . Relay T^2 also closes its contact 187^{T2} , causing indicator lamp eT^2 , shown in Fig. 6, to again become lighted. Relay T^2 also closes its contact 7^2 in the stick circuit of relay t^2 which, however, will continue de-energized until the leverman returns lever G^1 from its r position to some position in which contact 5^{G1} will be closed in the pick-up circuit of relay t^2 . Meanwhile, the circuit for the operating mechanism of signal $S1a$ continues open at contact 256^{t2} , and hence signal $S1a$ does not again clear until the leverman has, by the operation of lever G^1 , closed contact 5^{G1} and has thus energized relay t^2 , and has subsequently again reversed lever G^1 to its r position.

If, after a route has been arranged for a move such as from A to E as previously described, a train has entered the route, and it is then desired to provide a call-on signal indication to authorize a second train to enter the route while it is still occupied by the first train, the leverman will, while lever G^1 is still in its r position, reverse call-on lever g^2 , thereby opening contact 255^{g2} in the operating circuit of signal $S1a$ and closing contact 261^{g2} in the operating circuit of signal $S2$. The arm of signal $S2$ is then moved to its call-on position by current flowing through the path previously traced for signal $S1a$ as far as contact 254^{G1} , thence through contacts 261^{g2} , 262^{G3} , 308 of signal $S1a$, 309 of signal $S1b$, and the operating mechanism of signal $S2$ to terminal o . Signal control indicator lamp $eS2$ becomes lighted by a circuit including the operating circuit of signal $S2$ as just traced as far as contact 262^{G3} , and thence through the filament of lamp $eS2$ to terminal o . The movement of the arm of signal $S2$ to its call-on position opens contact 23 , operated by signal $S2$, in the circuit of relay N^1 which then becomes de-energized, opening the circuits of relays X^2 , X^3 , and X^4 as previously described in connection with the clearing of signal $S1a$. Since the operating circuit of signal $S2$ does not include a contact of relay T^2 or of relay t^2 , the arm of signal $S2$ is not caused to return to its stop position by the entrance of the train into section $A-F-E$. Signal $S2$ will therefore continue to display the call-on indication until the leverman moves either lever g^2 or lever G^1 away from its r position.

I will now assume that, with all parts of the apparatus again in their normal condition as previously described, the leverman arranges route 1 for a move from A to E and clears signal $S1a$, as also previously described, by the operation of lever G^1 to its r position. If now, after an eastbound train enters section $a-A$, de-energizing relay T^1 and, in turn, relay P^1 , the leverman should desire to send the train over some other route than route 1 , he will return lever G^1 to its n position, thereby opening contacts 254^{G1} in the operating circuit of signal $S1a$. If the leverman desires to send the train over route 2 , he will operate lever G^2 to its r position, opening contact 147^{G2} in the circuit of relay X^4 and, upon the further movement of lever G^2 , closing contact 139^{G2} in the circuit of relay R^4 . This contact does not, however, complete the circuit of relay R^4 which is already open at contact 99^{P1} due to approach locking relay P^1 having been de-energized by the train entering section $a-A$ with signal $S1a$ indicating "proceed."

The leverman therefore operates release J^1 in order to close contact 163 and thus complete a pick-up circuit of relay P^1 . After the beginning of the operation of release J^1 , a measured inter-

val of time must elapse before contact 163 will close, thus insuring that from the time of the return of the arm of signal S1a to its stop position, a similar interval of time must elapse before switch H4 can be reversed. Upon the closing of contact 99^{F1} by relay P1, relay R4 becomes energized by its circuit passing from terminal x, through contacts 97^{T2}, 98^{G6}, 99^{P1}, 100^{N1}, 101^{N6}, 135^{N3}, 136^{Q3}, 137^{VE}, wire 354, contact 139^{G2}, and the winding of relay R4 to terminal o. A branch path is also closed, passing from contact 101^{N6}, through contact 138^{h3} to wire 354.

Relay X4 being de-energized, and relay R4 now being energized, the reverse pick-up circuit for relay m4 is closed through front contacts of relay R4 and back contacts of relay X4. The reverse pick-up circuit for relay m4 is similar to that for relay m1 which passes from terminal x, through contact 33^{R1}, back contact 34^{X1}, winding of relay m1, back contact 36^{X1}, and contact 35^{R1} to terminal o. Relay m4 now closes its contacts in their reverse position, thus completing the reverse operating circuit for motor M4 of switch H4, shown in Fig. 1, through reverse contacts 345^{m4} and 350^{m4}. Current flows from battery L, through reverse contact 345^{m4}, armature 346 of motor M4, asymmetric unit i2, field winding 347, contact 349 of circuit controller y4, asymmetric unit i4, and reverse contact 350^{m4} back to battery L. Motor M4 then moves switch H4 to its reverse position. Contact 348 of circuit controller y4 becomes closed just after the beginning of this movement, and contact 349 becomes opened just before the completion of this movement. Due to the opening of contact 349, current ceases to flow through motor M4.

The movement of switch H4, to its reverse position, first opens the circuit of relay h4 by disconnecting contact 13 of circuit controller y4 from terminal 13a and contact 14 from terminal 14a, and then shunts relay h4 by a path including contact 13 connected with terminal 13c and contact 14 connected with terminal 14c. Relay h4 is, therefore, de-energized from the time of the disconnecting of contacts 13 and 14 from terminals 13a and 14a respectively until the time of connecting of contacts 13 and 14 with terminals 13b and 14b respectively. Upon the connecting of contacts 13 and 14 with terminals 13b and 14b respectively, current is supplied in the reverse direction to relay h4 which thereupon moves its contacts to their reverse position. Indicator lamp eR4, shown in Fig. 7, is then lighted by a circuit through a reverse contact of relay h4 similar to the circuit for lamp eR1 through contact 199^{h1} in its position 199b.

After relay P1 has been energized by the operation of release J1, the leverman must return release J1 to its normal position in order to close contact 245^{J1} in the operating circuit of signal S1b which governs over switch H4 reversed. With lever G2 in its r position, with release J1 returned to its normal position, and with the movement of switch H4 completed and relay h4 energized in its reverse direction, the operating mechanism of signal S1b is now supplied with current by a circuit passing from terminal x, through contacts 275^{N6}, 276^{G11}, 277^{G8}, 278^{G5}, 279^{G2}, 286^{G1}, 287^{G4}, 288^{G7}, 289^{G10}, 290^{h4}, 245^{J1}, 246^{h2}, 247^{h2}, 248^{G11}, 249^{G10}, 250^{G8}, 251^{G7}, 252^{G5}, 253^{G4}, 257^{G2}, 258^{g2}, 258^{h2}, and the operating mechanism of signal S1b to terminal o.

When the arm of signal S1b leaves its stop position, relay N1 becomes de-energized due to the opening of contact 24 of signal S1b. Ap-

proach locking relay P1 is then de-energized by the opening of its stick circuit at contact 160 of relay N1, since its pick-up circuit is already open at contact 159^{T1} due to the presence of a train in section a—A.

On account of the operation of lever G2 to its r position, the pick-up circuit of relay t2 is open at contact 6^{G2} but relay t2 continues energized by its stick circuit through contact 7^{T2}. By means of relay t2, contact 259^{t2} of which is included in the operating circuit of signal S1b, the stick operation of signal S1b is accomplished similarly to that of signal S1a which has been previously described.

As a train enters section A—F—E, the arm of signal S1b returns to its stop position similarly to the arm of signal S1a in the operation previously described. Because of the de-energization of relay N1, the circuit of relay R4 is open at contact 100^{N1}, and it continues open at contact 97^{T2} until after the train has left section A—F—E and relay T2 has again become energized.

Assuming, now, that all parts of the apparatus are again in their normal condition, and that the leverman desires to arrange for a traffic move over route 3 from A to D, he will reverse lever G3 to its r position, thereby opening contact 78^{G3} in the circuit of relay X2, and closing contact 72^{G3} in the circuit of relay R2. With relay R2 energized and relay X2 de-energized, polarized relay m2 will be energized in its reverse direction. Current will then be supplied in the reverse direction through reverse contacts of relay m2 to motors M2 and M2a, not shown in the drawing by a circuit similar to that shown for motors M3 and M3a. The circuits for each of the motors M3 and M3a are, after passing through the contacts 345^{m3} and 350^{m3}, similar to the circuits already described for motor M4 after passing through contacts 345^{m4} and 350^{m4}.

Upon the completion of the operation of switches H2 and H2a to their reverse position, polarized indication relay h2 will become energized in its reverse direction, closing its contact 297^{h2} in the operating circuit of signal S2, in which current now flows from terminal x, through contacts 310^{N5}, 314^{G3}, 315^{G6}, 317^{G9}, 215^{G11}, 214^{G11}, 213^{G8}, 212^{G7}, 211^{G5}, 210^{G4}, 209^{h3}, 297^{h2}, 298^{G11}, 299^{G10}, 300^{G8}, 301^{G8}, 302^{G7}, 303^{G6}, 304^{J1}, 305^{G3}, 308 of signal S1a, 309 of signal S1b, and the operating mechanism of signal S2 to terminal o. The arm of signal S2 then moves to its proceed position, opening the circuit of relay N1 at contact 23, and relay N1 in turn opening, at its contact 160, the stick circuit of relay P1.

Upon the de-energization of relay T1, relay P1 becomes de-energized as previously described. Upon the deenergization of relay N1, the circuit of relay R2 is opened at contact 68^{N1}, and contact 69^{F1} is opened in the circuit of relay R2 after the de-energization of relay T1.

When a train de-energizes relay T2, contact 71^{T2} also becomes opened in the circuit of relay R2, and, as the train continues into section B—C—D, relay T3 becomes de-energized, opening its contact 43^{T3} in the circuit of relay R2. As soon as the train leaves section a—A, relay T1 again becomes energized, closing a pick-up circuit previously traced for relay P1 through contact 159^{T1}. When the train leaves section A—F—E, relay T2 again becomes energized, closing its contact 71^{T2} in the circuit for relay R2, which is, however, still open at contact 43^{T3}. Relay R2 therefore continues de-energized from the time of its de-energization by relay N1 on ac-

count of the clearing of signal **S2**, until the train leaves section **B—C—D** permitting relay **T3** to again become energized.

- If, with all parts of the apparatus again in their normal condition, the leverman wishes to send a train by route **4**, he will reverse lever **G4** to its *r* position, thereby opening contact **79^{G4}** in the circuit of relay **X2**, and closing contact **74^{G4}** in the circuit of relay **R2**, and also opening contact **119^{G4}** in the circuit of relay **X3**, and closing contact **107^{G4}** in the circuit of relay **R3**. Relays **R2** and **R3** being energized while relays **X2** and **X3** are de-energized, polarized relays **m2** and **m3** are now energized in their reverse direction causing switches **H2**, **H2a**, **H3**, and **H3a** to be operated to their reverse positions. Relays **h2** and **h3** then become energized in the reverse direction, and close their contacts in their reverse position, causing indicator lamps **eR2** and **eR3**, shown in Fig. 7, to be lighted. Contacts of relays **h2** and **h3**, in their reverse positions, complete a circuit for the operating mechanism of signal **S2** passing from terminal *x*, through contacts **229^{N6}**, **230^{G10}**, **231^{G7}**, **238^{G4}**, **239^{G1}**, **240^{G11}**, **241^{G8}**, **242^{G5}**, **243^{G2}**, **244^{h4}**, **245^{J1}**, **291^{G1}**, **292^{G2}**, **293^{G3}**, **294^{G6}**, **295^{G5}**, **296^{h3}**, **297^{h2}**, **298^{G11}**, **299^{G10}**, **300^{G9}**, **301^{G8}**, **302^{G7}**, **303^{G6}**, **304^{J1}**, **306^{G4}**, **308** of signal **S1a**, **309** of signal **S1b**, and the operating mechanism of signal **S3** to terminal *o*.
- Upon the clearing of signal **S2**, relay **N1** becomes de-energized as before, opening the stick circuit of relay **P1** and closing the lighting circuit of indicator lamp **eN1**. Relay **N1**, upon becoming de-energized, also opens its contact **68^{N1}** in the circuit of relay **R2**, and contact **100^{N1}** in the circuits of relays **R3** and **X4**, causing the reverse stick circuits of relays **m2** and **m3** and the normal stick circuit of relay **m4** to be closed.

Upon the de-energization of relay **T1** by an approaching train, relay **P1** becomes de-energized by the opening of contact **159^{T1}**. Relay **P1** then opens its contact **180** in the stick circuit of route locking relay **VE**.

As the train proceeds further, and de-energizes relay **T2**, a pick-up circuit of relay **VE** is broken at contact **177^{T2}**, and relay **VE** is thereby de-energized since contact **179^{h3}**, in a second pick-up circuit of relay **VE**, is open because of the reverse energization of relay **h3**. Relay **VE**, becoming de-energized, opens its contact **137^{VE}** in the circuit of relay **X4**. Contact **138^{h3}** in the branch path around contact **137^{VE}** is already open, due to the reverse energization of relay **h3**. It follows that relays **R2**, **R3**, and **X4** have first become de-energized when relay **N1** has become de-energized, and that these relays then continue de-energized until the train has passed out of section **A—F—E**.

In order to arrange for a traffic move over route **7** from **B** to **E**, the leverman reverses lever **G7** to its *r* position, thus opening the circuit of relay **X3** at contact **111^{G7}**, and closing the circuit of relay **R3** at contact **111^{G7}**. Relay **m3** is then energized in its reverse direction, causing switches **H3** and **H3a** to be moved to their reverse positions. Relay **h3** then becomes energized in its reverse direction, completing an operating circuit for signal **S3** passing from terminal *x*, through contacts **229^{N6}**, **230^{G10}**, **236^{G7}**, **237^{G4}**, **239^{G1}**, **240^{G11}**, **241^{G8}**, **242^{G5}**, **243^{G2}**, **244^{h4}**, **245^{J1}**, **291^{G1}**, **292^{G2}**, **293^{G3}**, **294^{G6}**, **295^{G5}**, **296^{h3}**, **208^{h2}**, **207^{G5}**, **206^{G4}**, **205^{G3}**, **204^{J3}**, **274^{h1}**, **273^{G11}**, **272^{G10}**, **271^{G8}**, **322^{G7}**, and the operating mechanism of signal **S3** to terminal *o*.

The arm of signal **S3**, upon leaving its stop position, opens its contact **21**, causing relay **N3** to be de-energized. Relay **N3** thereupon opens its

contact **169** in the stick circuit of relay **Q3**, thus causing relay **Q3** to be de-energized. Relay **N3**, upon becoming de-energized, also opens the circuits of relays **X1** and **X2** at contact **46^{N3}**; opens the circuit of relay **R3** at contact **102^{N3}**; and opens the circuit of relay **X4** at contact **135^{N3}**, contact **138^{h3}** in the branch path around contact **135^{N3}** having been previously opened due to the reverse energization of relay **h3**. Relay **Q3**, upon becoming de-energized, opens its contact **44^{Q3}** in the circuits of relays **X1** and **X2**; opens its contact **105^{Q3}** in the circuit of relay **R3**; and opens its contact **136^{Q3}** in the circuit of relay **X4**. Relay **Q3** can again become energized only by a train proceeding into section **B—C—D** and de-energizing relay **T3**, or by the operation of time releasing device **J3**. Hence, if a train proceeds through section **B—C—D** by the route arranged from **B** to **E**, relay **Q3** will become energized by its pick-up circuit through contact **171^{T3}**. In order that relay **Q3** will continue energized after the train leaves section **B—C—D**, the leverman must move lever **G1** away from its *r* position, causing signal **S3** to again display the stop indication, and thereby completing the circuit of relay **N3** which in turn completes the stick circuit of relay **Q3** through its contact **169**.

As the train passes signal **S3**, de-energizing relay **T3**, route locking relay **VE** becomes de-energized due to the opening of contact **178^{T3}** in one of the pick-up circuits for relay **VE**, the other pick-up circuit for relay **VE** being already open at contact **179^{h3}** and the stick circuit for relay **VE** being already open at contact **181** of relay **Q3**. Relay **VE** therefore opens its contact **137^{VE}** in the circuit for relay **X4**. The circuit for relay **X4** continues open at contacts **137^{VE}** and **138^{h3}**, even if the leverman returns signal **S3** to its stop position causing relay **N3** to close its contact **135^{N3}** before the train has de-energized relay **T2** which operates contact **97^{T2}** in the circuit for relay **X4**.

For westbound moves, the operation is similar to that described for eastbound moves except that the levers **G** will be moved to their *b* or *p* positions instead of to their *f* or *r* positions. As an example, for arranging route **1** and clearing signal **S6** for a move from **E** to **A**, lever **G1** will be operated to its *p* position, completing, when switches **H2**, **H3** and **H4** are in their normal positions, a circuit for signal **S6** passing from terminal *x*, through contacts **332^{N1}**, **333^{G1}**, **334^{G2}**, **253^{G4}**, **252^{G5}**, **251^{G7}**, **250^{G8}**, **249^{G10}**, **248^{G11}**, **247^{h2}**, **246^{h3}**, **245^{J1}**, **243^{G2}**, **242^{G5}**, **241^{G8}**, **240^{G11}**, **337^{G1}**, and the operating mechanism of signal **S6** to terminal *o*.

Considering, now, the operation of the second form of apparatus embodying my invention, all parts of the apparatus as shown are in their normal condition as already stated in connection with the first form of apparatus shown in Figures 1 to 10 inclusive.

I will assume that, with the second form of apparatus, the leverman desires to send a train from **A** to **E**. He therefore reverses lever **G1** to its *r* position and lever **G6** to either its *r* or its *f* position. Current now flows to the operating mechanism of signal **S1a** as shown in Fig. 14, passing from terminal *x* through contacts **409^{N6}**, **410^{G7}**, **411^{G6}**, **412^{h4}**, **417^{J1}**, **418^{h3}**, **419^{h2}**, **420^{G1}**, **421^{G6}**, **422^{T2}**, and the operating mechanism of signal **S1a** to terminal *o*. Signal control indicator lamp **eS1a** is lighted by current flowing over the same path as far as contact **422^{T2}**, thence through lamp **eS1a** to terminal *o*. The operation of back lock-

ing relay N_1 , approach locking relay P_1 , and detector track circuit relay T_2 in opening the circuits of relays X_2 , X_3 , and X_4 and keeping these circuits open from the time signal S_1a de-energizes relay N_1 until a train moves out of section A—F—E is the same as described in connection with the first form of apparatus.

In order to give a call-on indication of signal S_2 , lever G_1 being in its r position, and either lever G_6 or G_7 being in either the f or the r position, the leverman operates push button U_2 , shown in Fig. 11, thereby closing the pick-up circuit of relay K_2 shown in Fig. 15, and which passes from terminal x , through contacts 440^{G_1} and 441^{U_2} , and the winding of relay K_2 to terminal o . Relay K_2 then continues energized by its stick circuit until the leverman again operates lever G_1 away from its r position. The energization of relay K_2 completes the operating circuit for signal S_2 passing over the path already traced for signal S_1a as far as contact 420^{G_1} , thence through contacts 425^{G_2} , 426^{K_2} , 430 of signal S_1a , 431 of signal S_1b , and the operating mechanism of signal S_2 to terminal o .

With the second form of apparatus, the procedure for changing a route, when an eastbound train is approaching point A while signal S_1a , S_1b , or S_2 is indicating "proceed", includes the operation of time releasing device J_1 as already described in connection with the first form of apparatus, and the procedure for changing a route when signal S_3 , or S_4 has de-energized relay Q_3 , by opening the circuit of relay N_3 , is as already described in connection with the first form of apparatus.

To arrange for a move over route 3, from A to D, the leverman reverses lever G_2 to its r position and lever G_5 to either its r or its f position. For a move over route 4, from A to E, the leverman reverses lever G_2 to its r position, and lever G_6 to either its r or its f position. For a move over route 6, from B to D, the leverman reverses lever G_3 to its r position, and lever G_5 to either its r or its f position.

The operation for each part of the second form of apparatus is, for westbound moves, similar to that for eastbound moves, except that levers G_5 , G_6 , and G_7 are operated to the p position, and levers G_1 , G_2 , G_3 , and G_4 are operated to either the b or the p position. As an example, in order to arrange for a move over route 1, from E to A, the leverman reverses lever G_6 to its p position, and lever G_1 to either its p or its b position. For a move over route 4, from E to A, the leverman reverses lever G_6 to its p position, and lever G_2 to either its p or its b position. For a move over route 1, from E to B, the leverman reverses lever G_6 to its p position, and lever G_3 to either its p or its b position.

I have described, for a few typical traffic moves, the operation of each of the two forms of apparatus embodying my invention. From those descriptions and the preceding general description, the operation of the apparatus for every other possible traffic move will be readily understood by reference to the drawings.

In various other interlocking systems, mechanical interlocking of the levers is provided, each route is controlled by a plurality of levers, and an indication lock arrests the movement of each lever, during its operation, until a given indication has been received. My invention, on the other hand, does not require either interlocking or indication locking of levers, and in its first form the track switches in each route and a re-

spective signal are controlled by only one operation of only one lever, and in its second form the track switches in each route and a respective signal are controlled by only one operation of each of only two levers. My invention, nevertheless, in each of its two forms provides approach locking, stick locking, route locking, detector track circuit locking, interlocking between various routes, interlocking between switches and signals, and control of the operation of switches and signals, as well as performing various other well-known functions of a railway interlocking system.

Although I have herein shown and described only two forms of multiple control apparatus embodying my invention, it is understood that various changes and modifications may be made therein within the scope of the appended claims without departing from the spirit and scope of my invention.

Having thus described my invention, what I claim is:

1. In combination with a plurality of devices each of which is responsive to a suitable form of energy and in a manner according to the manner of application of said energy thereto, a plurality of partly inter-inclusive groups of said devices, a manually operable means for each of said groups, means controlled by each of certain said manually operable means for applying energy in a given manner to some of the said devices in its group and in a given different manner to the other said devices in the same group, and means controlled by each of the other manually operable means for applying energy in one manner to all the devices in its group.

2. In combination with a plurality of devices each of which is responsive to a suitable form of energy and in a manner according to the manner of application of said energy thereto, a plurality of manually operable means, one group of a plurality of partly inter-inclusive groups of said manually operable means for each of said devices, one group of a plurality of second partly inter-inclusive groups of said manually operable means for each of said devices, means for controlling the application of energy in a given manner to each of said devices by any one of its second group of manually operable means.

3. In combination with a plurality of devices each of which is responsive to a suitable form of energy and in a manner according to the manner of application of said energy thereto, a plurality of manually operable means, one group of a plurality of partly inter-inclusive groups of said manually operable means for each of said devices, means for controlling the application of energy in a given manner to each of said devices by any one of its group of manually operable means, and means for controlling the application of energy in a second given manner to each of said devices by all of its group of manually operable means.

4. In combination with a plurality of devices each of which is responsive to a suitable form of energy and in a manner according to the manner of application of said energy thereto, a plurality of manually operable means, one group of a plurality of partly inter-inclusive groups of said manually operable means for each of said devices, one group of a plurality of second partly inter-inclusive groups of said manually operable means for each of said devices, means for controlling the application of energy in a given man-

ner to each of said devices by any one of its first group of manually operable means, and means for controlling the application of energy in a second given manner to each of said devices by all 5 of its first group of manually operable means or by any one of its second group of manually operable means.

5. In combination, a plurality of devices each having a normal and a reverse position, a plurality of manually operable means, one group of a plurality of groups of said manually operable means for each of said devices, means for controlling the operation of each of said devices to its reverse position by any one of its group of 10 manually operable means, means for controlling the operation of each of said devices to its normal position by all of its group of manually operable means, a plurality of second devices, one group of a plurality of groups of said manually operable 15 means for each of said second devices, and means for controlling the energization of each of said second devices by all of its group of said manually operable means and by certain of said first devices.

25. 6. In combination with a plurality of devices each of which is responsive to a suitable form of energy and in a manner according to the manner of application of said energy thereto, a plurality of manually operable means, a first and a second 30 and a third control means for each of said devices, a group of said manually operable means for each said first control means, means controlled by any one of its said group of manually operable means for energizing each said first control means, 35 means controlled by all of said group of manually operable means for energizing the said second control means for the same device, means controlled by each said first control means for energizing in the reverse direction the third control 40 means for the same device, means controlled by each said second control means for energizing in the normal direction the third control means for the same device, and means for applying energy to each said device in a first given manner or 45 in a second given manner according as its said third control means is energized in the normal or the reverse direction respectively.

7. In combination with a plurality of first devices each of which is responsive to a suitable 50 form of energy and in a manner according to the manner of application of said energy thereto, a plurality of manually operable second devices each having a normal and a reverse position, a first and a second neutral control relay and a polarized control relay for each of said first devices, a group of said second devices for each said 55 first control relay, means controlled by any one of its group of second devices in the reverse position for energizing each said first control relay, means controlled by every one of the same group 60 of second devices in its normal position for energizing the said second control relay for the same first device, means controlled by each said first control relay for energizing in its reverse direction the polarized control relay for the same first device, means controlled by each said second control relay for energizing in its normal direction 65 the polarized control relay for the same first device, and means for applying energy in a first or a second given manner to each of said first devices according as its polarized relay is energized in the reverse or the normal direction respectively.

8. In combination with a plurality of first 70 devices each of which is responsive to a suitable

form of energy and in a manner according to the manner of application of said energy thereto, a plurality of manually operable second devices each having a normal and a reverse position, a first and a second neutral control relay and a polarized control relay for each of said first devices, a group of said second devices for each said first control relay, means controlled by any one of its group of second devices for energizing each 5 said first control relay, a group of said second devices for each said second control relay, means controlled by any one of its group of second devices for energizing each 10 said second control relay, means controlled by each said second control relay for energizing in the normal direction the polarized control relay for the same 15 first device, and means for applying energy to each of said first devices in a first or a second given manner according as its polarized relay is energized in the reverse or the normal direction respectively.

25. 9. In combination with a plurality of first devices each of which is responsive to a suitable form of energy, a plurality of second devices each of which is responsive to a suitable form of energy, a plurality of manually operable devices each 30 having a normal position and a first and a second reverse position, a group of said manually operable devices for each said first device, means for energizing each of said first devices when any one of its group of said manually operable devices 35 occupies either the first or the second reverse position, and means for applying said energy to each of said second devices when a certain said manually operable device occupies its second reverse position.

40. 10. In combination with a stretch of railway track, a plurality of traffic governing devices for directing traffic over said stretch of track and each of these devices responsive to a suitable form of energy and in a manner according to the manner of application of said energy thereto, a plurality of manually operable devices, a first and a second group of said manually operable devices for each said traffic governing device, means controlled by any one of its first group of manually operable 45 devices for applying energy to each of said traffic governing devices in a given manner, and means controlled by any one of its second group of manually operable devices for applying energy to each of said traffic governing devices in a second 50 given manner.

55. 11. In combination with a stretch of railway track, a plurality of traffic governing devices each having a normal and a reverse position for directing traffic over said stretch of track, a plurality of manually operable devices each having a normal and a reverse position, a group of said manually operable devices for each of said governing devices, means controlled by any one of its group of manually operable devices in the reverse position for operating each of said governing devices 60 to its reverse position, and means for controlling the operation of each of said governing devices to its normal position by contacts closed by all the members of its group of manually operable 65 devices while in their normal positions.

70. 12. In combination with a stretch of railway track, a plurality of traffic governing devices each having a normal and a reverse position for directing traffic over said stretch of track, a plurality of 75

manually operable devices each having a normal and a reverse position, a group of said manually operable devices for each of said governing devices, means for operating each of said governing devices to its reverse position when any one of its group of said manually operable devices is moved to its reverse position, means for controlling the operation of each of said governing devices to its normal position by contacts closed by all members of its group of manually operable devices while in their normal positions, a plurality of signals for governing traffic over said stretch of track including said governing devices, and means for clearing each of said signals when a given said manually operable device is moved to its reverse position while every other said manually operable device which controls a conflicting signal is in its normal position.

13. In combination with a stretch of railway track in which are included one or more traffic governing devices each having a normal and a reverse position and in which stretch of track are also included a plurality of routes by any one of which traffic can move within said stretch of track, a manually operable route device for each of said routes each having a normal and a reverse position, a signal for governing traffic over each of said routes, means for operating each of said governing devices to its reverse position when a said route device is moved to its reverse position for arranging any route which includes said governing device in its reverse position, means for controlling the restoration of each of said governing devices to its normal position by contacts closed by all said route devices which cause said governing device to be reversed, and means for clearing each said signal when every said governing device in the route controlled by said signal has been operated to the position required by said route and while a given route device is reversed.

14. In combination with a stretch of railway track in which are included one or more traffic governing devices each having a normal and a reverse position and in which stretch of track are also included a plurality of routes by any one of which traffic can move within said stretch of track, a manually operable route device for each of said routes each having a normal and a reverse position, means including a contact of a route device for causing each of said governing devices to occupy its normal position while the route device is in its reverse position for arranging a route which includes said governing device in its normal position, and means for causing each of said governing devices to be operated to its reverse position when another said route device is moved to its reverse position for arranging a route which includes said governing device in its reverse position.

15. In combination with a stretch of railway track in which are included one or more traffic governing devices each having a normal and a reverse position and in which stretch of track are also included a plurality of routes by any one of which traffic can move within said stretch of track, a manually operable route device for each of said routes each having a normal and a reverse position, means including a contact of a route device for causing each of said governing devices to occupy its normal position while the route device is in its reverse position for arranging a route which includes said governing device in its normal position, and means for causing each of said governing devices to be operated

to its reverse position when another said route device is moved to its reverse position for arranging a route which includes said governing device in its reverse position while none of said route devices is reversed for arranging a route which includes said governing device in its normal position.

16. A railway interlocking system, comprising a stretch of railway track in which there is a plurality of railway track switches each having a normal and a reverse position and in which said switches can be so arranged as to form a plurality of traffic routes, a manually operable lever for each of said routes each having a normal position and a first and a second reverse position as well as a third and a fourth reverse position, a normal and a reverse control relay for each of said switches, a control circuit for each said reverse control relay including in multiple with each other contacts closed by operating to any of their four reverse positions the levers for routes which include the respective switch in its reverse position, a control circuit for each said normal control relay including a series path through contacts closed by the normal position of all said levers associated in the control of said reverse control relays and multiple paths through contacts closed by operating to any of their four reverse positions the levers for routes which include the respective switch in its normal position, a signal adjacent each end of each of said routes respectively for governing the movement of traffic in each direction over the route, a polarized control relay for each of said switches, a normal pick-up circuit for each said polarized relay controlled by front contacts of the respective said normal control relay, a reverse pick-up circuit for each said polarized relay controlled by front contacts of the respective said reverse control relay and by back contacts of the respective normal control relay, normal and reverse stick circuits for each said polarized relay controlled by back contacts of the respective normal and reverse control relays, means for controlling the operation of each of said switches to its reverse or its normal position according as the contacts of its polarized relay are closed in their reverse or normal position respectively, and an operating circuit for each of said signals controlled by contacts closed by the levers for all conflicting routes while the levers for said conflicting routes are in the normal position and by a contact of the lever for the route controlled by said signal closed while said lever is in its second or its fourth reverse position according as said signal controls traffic in the one direction or in the opposite direction respectively over the said route.

17. In combination, a plurality of partly inter-inclusive groups of devices, a plurality of second devices each of which is associated with one of said partly inter-inclusive groups of said first devices respectively, a plurality of manually operable instruments each having a first and a second position and each of which is associated with one of said groups of first devices respectively, means controlled by each said instrument when in its said first or its said second position for controlling its group of first devices, and means controlled by each said instrument when in its said second position for controlling the second device which is associated with its group of first devices.

18. In combination, a stretch of railway track including a plurality of switches which are capable of arrangement into a plurality of routes, a

manually operable device having a first and a second position for each of said routes, means controlled by each said manually operable device when in its first position or its second position for 5 arranging the switches in its route, a signal for each route, and means controlled by each said manually operable device when in its second position for controlling the signal for its route.

19. In combination, a stretch of railway track 10 including a plurality of switches which are capable of arrangement into a plurality of routes, a signal for each of said routes, a manually operable device for arranging the switches into each of said routes and each having a normal 15 and a reverse position and each controlling normal contacts which are closed when the device is in its normal position and each controlling a reverse contact which is closed when the device is in its reverse position, and a control 20 circuit for each of said signals controlled by the reverse contact of the manually operable device for its route and by a normal contact of the device for another route which intersects the route with which the signal is associated.
20. In combination, a stretch of railway track 25 including a plurality of intersecting routes, a signal for each direction of traffic of each of said routes, a plurality of mutually mechanically independent manually controllable devices one 30 for each of said routes, a plurality of partly inter-inclusive groups of said devices, and a control circuit for each of said signals controlled by a respective one of said groups and including a contact which is so controlled by the opposing 35 signal for the same route that it becomes closed when the arm of the opposing signal for the same route is indicating stop.

21. In combination, a stretch of railway track including a plurality of switches which are capable of arrangement into a plurality of intersecting routes, a manually operable device for each of said routes, means operated by each of said devices for causing all the switches of its route to be arranged to form its route, a signal 40 for each of said routes, and means controlled by each of said devices for clearing the signal for its route when all the switches in the route occupy positions corresponding to the position of said device.

22. In combination, a stretch of railway track 45 including a plurality of switches which are capable of arrangement into a plurality of routes, a manually operable device having a first and a second reverse position for each of said routes, means operated by each of said devices when moved to either its first or its second reverse 50 position for causing all the switches of its route to be arranged to form its route, a signal for each direction of traffic of each of said routes, means controlled by each of said devices when moved to its first reverse position for controlling the signal for a given direction of traffic in its route, and means controlled by each of said devices when moved to its second reverse position for controlling the signal for the opposite 55 direction of traffic in its route.

23. In combination, a stretch of railway track 60 including a plurality of switches which are capable of arrangement into a plurality of routes, a manually operable device having a first and a second reverse position for each of said routes, means operated by each of said devices when moved to either its first or its second reverse 65 position for causing all the switches of its route to be arranged to form its route, means controlled

by each of said devices when moved to its first reverse position for governing traffic in a given direction in its route, and means controlled by each of said devices when moved to its second reverse position for governing traffic in the opposite direction in its route. 5

24. In combination, a railway track switch, a signal for governing traffic movements over said switch, a control circuit for said signal, a locking relay controlled by traffic conditions and by said 10 signal control circuit, a second locking relay controlled by said first locking relay and by traffic conditions, a locking circuit for said switch controlled by said first and by said second locking relays, and an indication means controlled by 15 said second locking relay.

25. In combination, a stretch of railway track including a plurality of switches which can be arranged in normal and reverse positions to form a plurality of routes over said stretch, a 20 control device for each of said routes operable to each of its control positions independently of the corresponding control device for each other route, and means controlled by each of said control devices and interlocked non-mechanically 25 with apparatus controlled by another said control device for operating all the switches in its route.

26. In combination, a stretch of railway track including a plurality of intersecting routes, one 30 or more traffic governing devices for each of said routes for governing traffic movements over the route, a control device for each of said routes operable to each of its control positions independently of the corresponding control de- 35 vice for each other route, and means controlled by each of said control devices and interlocked non-mechanically with apparatus controlled by another said control device for operating all the governing devices for its route. 40

27. In combination, a plurality of railway track switches which can be arranged to form a plurality of routes over a given stretch of track, a control device for each of said routes, signals for governing traffic movements over each of said 45 routes including auxiliary call-on signals for certain routes, means controlled by each of said control devices for operating all the switches in its route and for clearing the signal for its route, an auxiliary control device for each of said call-on signals, and means controlled by each of said auxiliary control devices for clearing its call-on signal if and only if a corresponding route control device is reversed for arranging the switches in a given route. 50

28. In combination, a plurality of railway track switches which can be arranged to form a plurality of routes over a given stretch of track, a control device for each of said routes, call-on signals for certain of said routes, means including each of said control devices for operating all 60 the switches in its route, an auxiliary control device for each of said call-on signals, and means including each of said auxiliary control devices respectively for clearing its signal if and only if a corresponding route control device is reversed for arranging the switches in a given route. 65

29. In combination, a stretch of railway track including a plurality of track switches capable of forming a plurality of routes, a control de- 70 vice for each route operable to each of its control positions independently of the corresponding control device for each other route, means controlled by each of said devices and interlocked non-mechanically with apparatus controlled by 75

another said device for arranging all the switches of its route, and a control board on which said devices are indicated in locations corresponding to the locations of said routes.

5. In combination, a stretch of railway track including a plurality of traffic governing devices distributed among a plurality of routes, a control device for each route operable to each of its control positions independently of the corresponding control device for each other route, means controlled by each of said devices and interlocked non-mechanically with apparatus controlled by another said device for operating all the traffic governing devices of its route, and a control board 10 on which said devices are indicated in locations corresponding to the locations of said routes.

31. In combination, a railway track switch, a manually operable device having a first and a second position and a third position between said 20 first and second positions, means controlled by said device when in its first or second positions for operating said switch to a given position, and means including said device when in its third position for operating said switch to a second 25 position.

32. In combination, a railway track switch, an approach locking relay, a route locking relay, an indication device, and a circuit controlled by front contacts of said approach and route locking 30 relays for effecting operation of said switch and for energizing said indication device.

33. A railway interlocking system, comprising a stretch of railway track in which there is a plurality of railway track switches each having a normal and a reverse position and capable of arrangement in various combinations as to normal and reverse positions in said stretch of track so as to form a plurality of traffic routes, a plurality of manually operable levers each having 40 a normal position and a first and a second reverse position as well as a third and a fourth reverse position, a pair of said levers for each of said routes, means controlled by the pair of said levers for each route while in their first or second or third or fourth reverse positions for arranging the switches as required for such route, a signal adjacent each end of each of said routes for governing the movement of traffic through said stretch, circuits for clearing each said signal 50 at one end of the stretch, each including a contact closed by one lever of the pair of levers for a route governed by such signal while said lever is in either its first or its second reverse position and also including a contact closed by the other lever of said pair while said other lever is in its second reverse position only, and circuits for clearing each said signal at the other end of the stretch, each including a contact closed while one lever of the pair of levers for a route governed by such signal is in either its third or its fourth reverse position and also including a contact closed while the other lever of the same pair is in its fourth reverse position only.

34. In combination, a railway track switch included in a given position in each of a plurality of routes, a pair of mutually mechanically independent manually operable devices for each of said routes, means controlled by each of said 65 pairs of devices and interlocked non-mechanically with apparatus controlled by another said pair of devices for operating said switch to said given position, and means including one of the devices of each of said pairs for causing the operation of said switch to a second position.

35. In combination, a stretch of railway track including a plurality of partly inter-inclusive routes, a plurality of partly inter-inclusive pairs of mutually mechanically independent devices one for each of said routes, a signal for each direction of traffic for each of said routes, means controlled by each of said pairs of devices for clearing the signal for a given direction of traffic for its route, and means controlled by each of said pairs of devices for clearing the signal for the opposite direction of traffic for its route. 5

36. In combination, a stretch of railway track including a plurality of partly inter-inclusive routes, a plurality of partly inter-inclusive pairs of mutually mechanically independent devices each of which has a normal position and a first and a second reverse position, a signal for each of said routes, and means controlled by said pairs of devices in their first and second reverse 15 positions for controlling said signals. 20

37. In combination, a stretch of railway track including a plurality of partly inter-inclusive routes, a plurality of partly inter-inclusive pairs of mutually mechanically independent devices one pair for each of said routes and each of 25 said devices having a normal and a reverse condition, a signal for each of said routes, and means controlled by each of said pairs of devices for clearing the signal for its route when both devices of the pair are in the reverse condition. 30

38. Railway control apparatus comprising a track diagram constituting a miniature representation of a stretch of railway track including a plurality of partly inter-inclusive routes, a corresponding plurality of partly inter-inclusive pairs of manually operable devices which are located at opposite ends of the representations of said routes on said diagram, and route control apparatus responsive to the operation of said pairs of devices for controlling traffic movements 35 through said routes. 40

39. Railway control apparatus comprising a track diagram constituting a miniature representation of a stretch of railway track including a plurality of track switches which can be 45 arranged to form a plurality of routes over said stretch, a corresponding plurality of partly inter-inclusive pairs of manually operable devices which are located at opposite ends of the representation of said routes on said diagram, and switch 50 control apparatus governed by said devices for controlling the track switches to establish said routes.

40. In combination, a first, a second, and a third railway track switch, a first, and a second manually operable device each of which has a normal and a reverse position and each of which is mechanically independent of the other, means including said first device for controlling said first switch, means including said second device for controlling said second switch, and means controlled by both said devices for controlling said third switch when and only when both said devices are in their reverse position. 55

41. In combination, a plurality of railway track switches which can be arranged to form a plurality of routes over a given stretch of track, a control device for each of said routes, signals for governing traffic movements over each of said routes, with auxiliary call-on signals for 70 governing traffic movements over certain routes, means controlled by each of said control devices and interlocked non-mechanically with apparatus controlled by another said control device for operating all the switches in its route and for 75

clearing the signal for its route, an auxiliary control device for each of said call-on signals, and means controlled by each of said auxiliary control devices for clearing its call-on signal.

5 42. In combination, a stretch of railway track including a plurality of track switches capable of arrangement into a plurality of routes, a stick relay for each direction of traffic for each route end in said stretch, a first manually operable 10 device for each of said stick relays, a second manually operable device for each of said stick relays, a pick-up circuit for each of said stick relays controlled by its said first manually operable device, a stick circuit for each of said stick 15 relays controlled by its said second manually operable device, and means controlled by each of said stick relays for arranging all the switches in its route.

20 43. In an interlocking system, the combination with a plurality of levers in an interlocking tower free to be moved to any position at any time, a traffic controlling device for each lever controlled by such lever and located at a distant way station, and a circuit including a contact of one of 25 said levers for controlling a particular traffic controlling device and also including contacts mechanically operated by other and conflicting traffic controlling devices closed only when such other conflicting traffic controlling devices are 30 in their non-conflicting positions.

44. In an interlocking system, the combination with a plurality of levers in an interlocking office each free to be moved to any position at any time, a wayside signal for governing traffic in a particular direction over a stretch of track, another wayside signal for governing traffic in the opposite direction over said stretch, and a circuit controlled by one of said levers and for controlling one of said signals and including contacts 35 closed only if said stretch of track is unoccupied and said other signal is in its stop condition.

45. In an interlocking system, the combination with a plurality of levers in an interlocking office each free to be moved to any position at any time, a wayside signal for governing traffic in a particular direction over a stretch of track, another wayside signal for governing traffic in the opposite direction over said stretch, a circuit for controlling one of said signals including a contact of one of said control levers and a contact closed only when the other signal is in its stop condition, and means in said interlocking tower for indicating the continuity of said circuit. 50

46. In an interlocking system, the combination with a plurality of levers in an interlocking office each free to be moved to any position at any time, a wayside signal for governing traffic in a particular direction over a stretch of track, another wayside signal for governing traffic in the opposite direction over said stretch, a circuit controlled by one of said levers and for controlling one of said signals and including contacts closed 55 only if said stretch of track is unoccupied and said other signal is in its stop condition, and means in said interlocking tower for indicating the continuity of said circuit.

47. In an interlocking system, the combination with a plurality of levers in an interlocking tower free to be moved to any position at any time, a traffic controlling device for each lever controlled by such lever and located at a distant way station, a circuit controlled by one of said levers for controlling a particular traffic controlling device including contacts controlled by other and conflicting traffic controlling devices closed only 60

when such other conflicting traffic controlling devices are in their non-conflicting positions, and means in said interlocking tower for indicating the continuity of said circuit.

5 48. In an interlocking system, the combination with a plurality of levers in an interlocking office each free to be moved to any position at any time, a wayside signal for governing traffic in a particular direction over a stretch of track, another wayside signal for governing traffic in the opposite direction over said stretch, a circuit for controlling one of said signals including a contact of one of said control levers and a contact closed only when the other signal is in the stop condition, and means in said interlocking tower for indicating when said contacts in said circuit are closed. 10

20 49. In an interlocking system, the combination with a plurality of levers in an interlocking office each free to be moved to any position at any time, a wayside signal for governing traffic in a particular direction over a stretch of track, another wayside signal for governing traffic in the opposite direction over said stretch, a main circuit path for one of said signals including a contact of one of said control levers and a contact closed only when the other signal is in the stop condition, a circuit for controlling said one signal including said main circuit path, and means in said interlocking tower for indicating the continuity of said main circuit path. 25

30 50. In an interlocking system, the combination with a plurality of levers in an interlocking office each free to be moved to any position at any time, a wayside signal for governing traffic in a particular direction over a stretch of track, another wayside signal for governing traffic in the opposite direction over said stretch, a main circuit path for one of said signals including means controlled by one of said levers and including contacts closed only if said stretch of track is unoccupied and said other signal is in its stop condition, a circuit for controlling said one signal including said main circuit path, and means in said interlocking tower for indicating the continuity of said main circuit path. 35

40 51. In an interlocking system, the combination with a plurality of levers in an interlocking tower free to be moved to any position at any time, a traffic controlling device for each lever controlled by such lever and located at a distant way station, a main circuit path for a particular traffic controlling device including means controlled by one of said levers and including contacts controlled by other and conflicting traffic controlling devices closed only when such other conflicting traffic controlling devices are in their non-conflicting positions, a circuit including said main circuit path for controlling said particular traffic controlling device, and means in said interlocking tower for indicating the continuity of said main circuit path. 45

55 52. In combination, a stretch of railway track including a first switch and a second switch, a first signal and a second signal for governing traffic movements over said stretch of track, a first lever and a second lever each having a normal position and a first and a second reverse position, means controlled by said first lever in either its first or its second reverse position for reversing said first switch, means controlled by said first lever in its normal position for returning said first switch to its normal position, means controlled by said second lever in either its first or its second reverse position for reversing said second 60

switch, means controlled by said second lever in its normal position for returning said second switch to its normal position, means controlled by both said levers when each is in its first reverse position for clearing said first signal, and means controlled by both said levers when each is in its second reverse position for clearing said second signal.

53. In combination, a stretch of railway track including a plurality of switches capable of being arranged to form a plurality of routes, a plurality of partly inter-inclusive pairs of levers one pair for each of said routes and each of said levers being free to be moved at any time to a first or a second reverse position, means controlled by one or the other lever of each pair of levers for arranging each switch in the associated route in the position required for the route, a signal for each direction of traffic movement over each of said routes, a signal circuit controlled jointly by both levers of each pair in the first reverse position for clearing a given signal for the associated route, and a second signal circuit controlled jointly by both levers of each pair in the second reverse position for clearing the signal for the opposite direction of traffic movement over the associated route.

54. In combination, a stretch of railway track including a plurality of switches capable of being arranged to form a plurality of routes, a plurality of partly inter-inclusive pairs of levers one pair for each of said routes and each of said levers operable to a first or a second or a third or a fourth reverse position, means controlled by one or the other lever of the pair of levers for each route for arranging each switch in the associated route in the position required for the route, a signal for each direction of traffic movement over each of said routes, means controlled by one of the levers of each pair in either its first or its second reverse position and by the second lever of the same pair in its second reverse position only for clearing a given signal for the associated route, and means controlled by the second lever of each pair in either its third or its fourth reverse position and by the first lever of the same pair in its fourth reverse position only for clearing the signal for the opposite direction of traffic movement over the associated route.

55. In combination, a stretch of railway track including a plurality of switches which are capable of being arranged to form a plurality of routes, a plurality of partly inter-inclusive pairs of manually controllable devices one pair for each of said routes, a signal for each of said routes, means controlled by each of said pairs of manually controllable devices when operated to given positions for clearing the signal for the associated route, a call-on signal in addition to one of said first signals for a given one of said routes, a manually controllable call-on device for said call-on signal, a call-on stick relay having a pick-up circuit and a stick circuit one of which is controlled by said call-on device and the other of which can be closed by one of the devices of the pair of manually controllable devices for said given route when in a position for clearing the first signal for said given route, and means controlled by said call-on stick relay when energized for clearing said call-on signal if traffic conditions are not favorable for the first signal for the same route to be cleared.

56. In combination, a stretch of railway track, a first signal for governing traffic movements over said stretch, a manually operable device, a nor-

mally open contact manually operable to a closed position, means manually set into operation by said manually operable device for effecting operation of said signal to direct traffic movements over said stretch under given traffic conditions, a 5 call-on signal for governing traffic movements into said stretch, a call-on stick relay, a pick-up circuit for said call-on stick relay closed by said normally open contact in cooperation with said manually operable device when said manually 10 operable device is in the position for effecting operation of said first signal, a stick circuit controlled by said manually operable device for retaining said stick relay in the energized condition as long as said manually operable device remains in the position for effecting operation of said first signal, and means controlled by said call-on stick relay for clearing said call-on signal under other traffic conditions than said given 15 traffic conditions.

57. In combination, a stretch of railway track including a plurality of switches capable of being arranged to form a plurality of routes, a manually operable device for each of said routes having a first and a second position, means controlled by each said manually operable device when in either its first position or its second position for arranging the switches in the positions required for its route, a signal for each route, and means controlled by each said manually operable device for clearing the signal for its route only if the manually operable device is in its second position.

58. In combination, a stretch of railway track including a plurality of switches capable of being arranged to form a plurality of routes, a manually operable device for each of said routes having a first and a second position, means controlled by each said manually operable device when in either its first position or its second position for arranging the switches in the positions required for its route, and means controlled by each said manually operable device for directing traffic movements over its route only if the manually operable device is in its second position.

59. In combination, a stretch of railway track including a plurality of switches which are capable of arrangement into a plurality of routes, a manually operable device for each of said routes having a first and a second and also a third and a fourth position, means controlled by each of said manually operable devices when in any of its said four positions for arranging the switches for its route in the positions required for its route, 55 means controlled by each of said manually operable devices in only its second position for directing traffic movements in a given direction over its route, and means controlled by each of said manually operable devices in only its fourth position for directing traffic movements in the opposite direction over its route.

60. In combination, a stretch of railway track comprising two or more routes each of which includes one or more switches, a signal for each 65 of said routes, a manually operable route lever for each of said routes, means controlled by manipulation of said route levers for arranging the switches of said routes in the positions required for the routes and for clearing said signals for said routes, a stick relay for a given one of said signals, a pick-up and a stick circuit for said stick relay one of which is closed only under given traffic conditions and the other of which is closed when the route lever for the associated 70

75

- route is in a given position but which is opened when the route lever is manipulated for clearing the signal for the route, and means controlled by said stick relay to prevent clearing of said signal by the route lever for the associated route except when said stick relay is energized.
61. In combination, a railway track switch, a normal control relay and a reverse control relay for said switch, manually controllable means for selectively energizing said normal and reverse control relays under given traffic conditions, indication means controlled by said given traffic conditions for indicating when said normal and reverse control relays can be energized by said manually controllable means, and means controlled by said normal and reverse control relays for operating said switch to its normal or its reverse position according as said normal control relay or said reverse control relay is energized.
62. In combination, a railway track switch, a manually controllable pole-changer, a polarized control relay, means controlled by said pole-changer for energizing said relay in the normal and the reverse direction, a circuit controller operated in conjunction with said switch, a plurality of asymmetric units, a motor comprising a first and a second winding for moving said switch to its normal or its reverse position according as said motor is operated in the normal or the reverse direction, a normal circuit controlled by said relay when energized in the normal direction and by said circuit controller and asymmetric units for energizing said first and second windings in a given direction whereby said motor is operated in the normal direction, and a reverse circuit controlled by said relay when energized in the reverse direction and by said circuit controller and asymmetric units for energizing said first winding in the same direction as before but energizing said second winding in the opposite direction whereby said motor is operated in the reverse direction.
63. In combination, a plurality of railway traffic governing devices, a source of current, a main circuit including said source, a plurality of branch paths, a circuit including said main circuit and one of said branch paths for controlling each of said devices respectively, and indication means connected in multiple with said branch paths and controlled by said main circuit.
64. In an interlocking system for a plurality of railway tracks interconnected to form a plurality of routes, signals for governing traffic movements over said routes, a manually controllable entrance contact and a manually controllable exit contact for each end of each route, an indicating lamp associated with each of said entrance contacts, means effective upon the closing of an entrance contact and an exit contact for clearing the signal for the route defined by said contacts, and means controlled by both of the operated entrance and exit contacts for lighting the indicating lamp associated with the operated entrance contact.
65. In an interlocking system for a plurality of railway tracks interconnected to form a plurality of routes, signals at the opposite ends of said routes for governing traffic movements over the routes, a manually controllable entrance contact and a manually controllable exit contact for each end of each of said routes, an indicating lamp associated with each of said entrance contacts, means controlled by the closing of the entrance contact for a given end of each route and of the exit contact for the opposite end

of each route for clearing the signal at said given end of the corresponding route, means controlled by the closing of the exit contact for said given end of each route and of the entrance contact for the opposite end of each route for clearing the signal at said opposite end of the corresponding route, and means effective upon the closing of both the entrance and exit contacts of each pair of contacts for lighting the indicating lamp associated with the entrance contact of the same pair of contacts.

66. A railway switching system, comprising a stretch of railway track including a plurality of track switches capable of arrangement in various combinations to form a plurality of interconnecting routes, a plurality of manually controllable devices, means controlled by each said device for controlling the arrangement of one or more of the track switches in the corresponding route, signals for governing the movement of traffic in each direction over each of said routes, a pair of said devices for each of said routes, and a signal circuit for each direction for each route controlled by the pair of devices for such route for clearing the signal for the corresponding direction of traffic movement over such route.

67. In combination, a track layout including a plurality of track switches normally forming main line routes but adapted to be reversed to form a plurality of different traffic routes, a route control device for each route end, each said route control device being operable in either direction from its normal position, switch control means controlled by said route control devices for controlling the track switches to establish the different routes, signals at the ends of the routes for governing the movement of traffic in opposite directions through said layout, means effective only when the two route control devices for the opposite ends of a route are both moved in the same direction to clear the signal at one end of said route or the other in accordance with the direction in which the route control devices are moved, such signal being cleared only when the track switches occupy the proper positions to establish said route, and means for restoring each reversed track switch to normal upon the restoration to normal of said route control devices.

68. In combination, a track layout including a plurality of track switches adapted to be arranged to form a plurality of different traffic routes, a route control device for each route end, each said route control device being operable in either direction from its normal position, switch control means controlled by said route control devices for controlling the track switches to establish the different routes, signals at the ends of said routes for governing the movement of traffic in opposite directions through said track layout, means effective only when the two route control devices for the opposite ends of a route are both moved in the same direction to clear the signal at one end of said route or the other to permit a train movement over the route in a direction corresponding to the direction in which said route control devices are moved, such signal being cleared only when the track switches occupy the proper positions to establish said route, and locking means controlled by said signals effective as long as a signal is at clear to prevent the response of the track switches of its route to the operation of any of said route control devices.

69. In combination, a track layout adapted to form a plurality of different traffic routes, signals at the ends of said routes for governing the movement of traffic in opposite directions through said track layout, a route control device for each route end, each said route control device being operable in either direction from its normal position, a control board comprising a miniature representation of the track layout having said route control devices disposed in positions corresponding with the ends of the establishable routes, and means effective only when the two route control devices for the opposite ends of a route are both moved in the same direction to clear the signal at one end of the route or the other in accordance with the direction in which said route control devices are moved.
70. In combination, a track layout adapted to form a plurality of different traffic routes, signals at the ends of said routes for governing the movement of traffic in opposite directions through said track layout, a route control device for each route end, each said route control device being operable in either direction from its normal position, means effective only when the two route control devices for the opposite ends of a route are both moved in the same direction to clear the signal at one end of the route or the other to permit a train movement over the route in the direction corresponding to the direction in which said route control devices are moved, and a control board comprising a miniature representation of the track layout having said route control devices disposed thereon in positions corresponding with the ends of the establishable routes to provide a visual indication of the direction of train movement permitted by the signal cleared as a result of the operation of said route control devices.
71. In combination, a track layout adapted to form a plurality of different traffic routes, signals at the ends of said routes for governing the movement of traffic in opposite directions through said layout, said signals including both a main signal and an auxiliary signal for each main line route through the layout, the clearing of the main signals only being dependent upon track conditions in said layout, a route control device for each route end, each said route control device being operable in either direction from its normal position, a control board comprising a miniature representation of the track layout having said route control devices disposed thereon in positions corresponding with the ends of the establishable routes, means effective only when the two route control devices for the opposite ends of a route are both moved in the same direction to clear the signal at one end of the route or the other in accordance with the direction in which said route control devices are moved, a call-on button on said diagram adjacent the entrance to each main line route, and means controlled by each call-on button when operated to clear the corresponding auxiliary signal provided the route control devices for the route governed by such signal have been operated and the associated main line signal is prevented from clearing by track conditions.
72. In an interlocking system for a plurality of railway tracks interconnected to form a plurality of routes, main signals at the ends of said routes for governing the movement of traffic in opposite directions over said routes, an auxiliary signal in addition to the main signal for a given
- direction of traffic movements for a given one of said routes, a route control device for each route end having a normal position and a first and a second reverse position, an auxiliary control device having a normal and a control position, means controlled by the two route control devices for the opposite ends of a route in their first reverse position under given traffic conditions for clearing a corresponding main signal for a given direction of traffic movements over such route, means controlled by the two route control devices for the opposite ends of a route in their second reverse position under given traffic conditions for clearing a corresponding main signal for the opposite direction of traffic movements over such route, and means controlled by said auxiliary control device in its control position and by the two route control devices for the opposite ends of said given route in the first or second reverse position for the corresponding direction of traffic movements for clearing said auxiliary signal.
73. In an interlocking system for a plurality of railway tracks interconnected to form a plurality, a route control device for each route end each of said routes having normal and reverse positions, an auxiliary control device for a given route having a normal and a control position, means controlled by the two route control devices for the opposite ends of any route in reverse positions under given traffic conditions for displaying a main signal indication for the corresponding route, and means controlled by said auxiliary control device in its control position and by the two route control devices for the opposite ends of said given route in reverse positions for displaying a call-on signal indication.
74. In combination, a stretch of railway track including a plurality of switches which can be arranged to form a plurality of routes, a circuit controlling device for each of said routes having a normal and a second position, and means set into operation by each of said circuit controlling devices when put into its second position for arranging all the switches of a corresponding route in positions required for the route only with one or more of the other circuit controlling devices in the normal position.
75. In combination, a stretch of railway track including a plurality of switches which can be arranged to form a plurality of routes, signals for governing traffic movements over said routes, a manually controllable device for each route end having a normal and a reverse position, means controlled by said manually controllable devices for arranging the switches in positions required for said routes, and a signal circuit for each route including contacts controlled by the track switches and other contacts closed upon the operation of the manually controllable devices for the opposite ends of the route to the reverse position, each such circuit being completed to clear the signal for governing traffic movements over such route automatically as soon as the track switches assume the positions required to establish such route.
76. In combination, a stretch of railway track including a plurality of switches which can be arranged to form a plurality of routes, signals for governing traffic movements over said routes, a manually controllable device for each route end having a normal and a reverse position, means controlled by said manually controllable devices for arranging the switches in positions required for said routes, and a signal circuit for each route

- including contacts controlled by the track switches and other contacts closed upon the operation of the manually controllable devices for the opposite ends of the route to the reverse position
- 5 for automatically clearing the signal for governing traffic movements over the corresponding route, only after the switches have been arranged in the positions required for such route.
77. In a switch and signal control system, a
- 10 control board having thereon a miniature representation of a portion of track including at least two track switches one of which is a facing switch and one of which is a trailed switch for a given direction of train movement over said track portion, manually operable buttons associated with the entrance and exit ends of said portion of track mounted on said control board in corresponding locations, switch control means for each of said track switches, circuit means responsive
- 15 to the operation of a button for the entrance end of said track portions for conditioning the switch control means for the trailed switch to a given position for that direction of train movement, circuit means responsive to the subsequent operation of the button for the exit end of said track portion for conditioning the switch control means for the other switch to a position to be trailed if there were a train movement in the other direction over said track portion.
- 20 78. In a switch and signal system for railroads, a control board having thereon a miniature representation of a stretch of track between two signals including at least two track switches diverging in opposite directions from said stretch,
- 25 means for operating said track switches and clearing the signal at a particular entrance point to said stretch including an entrance button for the entrance point to said stretch and an exit button for the exit point to said stretch mounted
- 30 on said diagram in corresponding locations, switch control means for each of said track switches, circuit means responsive to an operation of said entrance button for conditioning said switch control means for the nearest switch to
- 35 that point to cause the operation of that track switch to a given position, circuit means responsive to the operation of the exit button to condition the control means for the switch nearest to said exit point for causing an operation of that
- 40 switch to a given position, and a signal at said entrance point cleared in response to the operation of said entrance and exit buttons only after said track switches have been operated to said given positions.
- 45 79. In a route interlocking system for controlling traffic movements through a railway track layout comprising track sections interconnected by power operated track switches and having signals for governing traffic movements over the
- 50 routes formed by operating the switches to different positions, in which the operation of the switches is governed by locking relays to prevent the operation of each switch in a route when a signal governing traffic movements over such
- 55 route is at clear and also when that route is occupied by a train which is in or approaching the track section containing that switch, the combination of a control board comprising a track diagram representing the track layout with
- 60 route buttons mounted thereon adjacent the ends of the representations of the routes, with circuits controlled by the route buttons for governing the operation of the track switches and clearing the signals, said circuits being effective when a
- 65 desired route is manually indicated by the opera-
- tion of the route buttons adjacent the representations of its opposite ends with all conflicting route buttons in their normal positions to automatically establish that route by the operation of one or more track switches if required and to clear
- 70 the signal for the route identified by the operated buttons as soon as that route is established, together with indication lamps associated with said control board and controlled by said locking relays to indicate when each track switch is free to be operated, and other lamps controlled by the track switches to indicate when a route selected by operation of the route buttons is fully established.
- 75 80. In combination, a plurality of railway tracks interconnected by track switches to form a plurality of routes, signals at the ends of said routes for governing traffic movements in opposite directions over said routes, a manually operable route lever for each signal location having a normal position and a first and a second reverse position, each such lever being free to be moved to any of said positions at any time, means controlled by said levers for arranging said switches in the positions required for said routes,
- 80 a circuit for each route controlled by the levers for the signal locations at opposite ends of such route for automatically clearing the signal for a given direction of traffic movements over the route if both levers are placed in the first reverse position, and the track switches assume the positions required for the route, a circuit controlled by the same levers for automatically clearing the signal for the opposite direction of traffic movements over such route if both levers are placed in the second reverse position and the track switches assume the positions required for the route, and locking means controlled by each signal and effective as long as such signal is at clear to prevent the operation of the track
- 85 switches of its route in response to the operation of the levers for conflicting routes.
- 90 81. In combination, a plurality of railway track sections interconnected by track switches to form a plurality of routes, signals at the ends of said routes for governing traffic movements in opposite directions over said routes, a manually operable route lever for each signal location having a normal position and a first and a second reverse position, each said lever being free to be moved to any of said positions at any time, means controlled by said levers in the first or second reverse positions for reversing said switches as required for said routes, means controlled by said levers for returning said switches to the normal position, a circuit for each route controlled by the levers for the signal locations at opposite ends of such route for clearing the signal for a given direction of traffic movements over the route automatically if both levers are placed in the first reverse position, and the track switches assume the positions required for the route, a circuit controlled by the same two levers for clearing the signal for the opposite direction of traffic movements over such route if both
- 95 levers are placed in the second reverse position, and the track switches assume the positions required for the route, and locking means for each track switch effective to prevent its response to the operation of any of said levers when the track section containing the switch is occupied by a train.
- 100 82. In an interlocking system for railroads; a plurality of routes through a track layout; a sig-

5. nal for each route end for governing the movement of traffic through said layout, a single route device for each route end at each end of said track layout, each having a stop position and two clearing positions for opposite directions of traffic; and means requiring only a single operation of said route devices for the two opposite ends

of a route to corresponding clearing positions for automatically setting up that route through said track layout and clearing said signal governing traffic in a direction corresponding to the positions of said route devices. 5

LESTER E. SPRAY.

CERTIFICATE OF CORRECTION.

Patent No. 2,211,522.

August 13, 1940.

LESTER E. SPRAY.

It is hereby certified that error appears in the printed specification of the above numbered patent requiring correction as follows: Page 14, second column, line 13, claim 48, for "leevrs" read --levers--; page 17, second column, line 25, claim 73, after the syllable "rality" and before the comma insert the words --of routes--; line 26, same claim, strike out "each of said routes"; and that the said Letters Patent should be read with this correction therein that the same may conform to the record of the case in the Patent Office.

Signed and sealed this 8th day of October, A. D. 1940.

Henry Van Arsdale,

(Seal)

Acting Commissioner of Patents.
